BENCH

Douglas M. Ruth, 1901 NE. 18th St.,
Fort Lauderdale, Fla. 33305

Filed Feb. 17, 1971, Ser. No. 116,303

Term of patent 14 years

Int. Cl. D6—02

U.S. Cl. D6—60

FIG. 1

FIG. 2

FIG. 3

FIG. 4

FIG. 1 is a front perspective view of a bench showing my new design;

FIG. 2 is an end elevational view of the bench;

FIG. 3 is a front elevational view of the bench; and

FIG. 4 is a sectional view of the bench taken along plane 4—4 of FIG. 3 and looking in the direction of the arrows.

The end of the bench, not shown, is a mirror image of the end shown while the rear thereof is conventionally plain and unornamented.

I claim:

The ornamental design for a bench, as shown and described.
